UNITED STATES PATENT OFFICE

DANIEL E. HENNESSY, OF WATERTOWN, MASSACHUSETTS, ASSIGNOR TO LEWIS-SHEPARD COMPANY, OF WATERTOWN, MASSACHUSETTS, A CORPORATION OF MASSACHUSETTS

ELEVATING TRUCK WITH SAFETY LOCK

Application filed July 23, 1929. Serial No. 380,294.

This invention relates to improvements in elevating trucks and the principal object thereof is to provide safety mechanism for preventing injury to the operator by reason of a "flying lifting lever or tongue".

The invention more particularly relates to improvements in elevating trucks in which the load supporting means is raised step by step by mechanism operated by a downward swinging movement of the tongue to lift the load supporting means.

Where, during the lifting of the load supporting means, or when the load supporting means of an elevating truck is in raised position, the means for locking the same fails to engage or becomes disengaged, the descent of the load supporting means, particularly when heavily loaded, will cause the tongue to fly upwardly with great force and in some instances has seriously injured the operator of the truck. By the present invention a safety device is provided which will prevent the release of the locking mechanism while the tongue is so co-ordinated with the lifting means that the descent of the load supporting means will cause the lifting lever or tongue to fly upwardly.

A further object of the invention is to provide a safety device of the character above described which will not interfere with the proper steering of the truck.

A further object of the invention is to provide simple safety means of the character above specified of a rigid character and so constructed as always to be dependable.

These and other objects and features of the invention will more fully appear from the following description and the accompanying drawings and will be particularly pointed out in the claims.

A preferred embodiment of the invention is illustrated in the accompanying drawings as applied to an elevating truck operable to raise the load supporting means step by step of the type illustrated in Patent No. 1,445,838 granted to Lewis-Shepard Company assignee of Ralph M. Lovejoy February 20, 1923, and in view of the disclosure in such patent only so much of the truck is illustrated in the accompanying drawings as is

required to show the application of the present invention thereto.

In the drawings:

Fig. 1 is a perspective view of the front portion of an elevating truck of the type described having a detent for preventing depression of the pedal which releases the locking dog, the tongue being shown in elevated position and the detent swung to inoperative position to permit actuation of the pedal;

Fig. 2 is a similar view illustrating the detent in normal position to prevent depression of the pedal which releases the locking mechanism and showing the tongue in substantially horizontal steering position;

Fig. 3 is a detail view showing the pedal arm in cross section and illustrating in full lines the detent in inoperative position and in dotted lines the detent in operative position to prevent depression of the pedal; and

Fig. 4 is a detail view illustrating the mechanism for controlling and actuating the locking dog which retains the load supporting means in elevated position.

The elevating truck illustrated in the accompanying drawings comprises a wheel-supported main frame having side bars 1 connected at their forward ends by an arched head 2 having a central integral steering head 3 in which is mounted the steering post of the steering mechanism. The steering post is provided with a downwardly extending yoke 4 having at its ends bosses for the axle 5 of the front wheel or wheels 6. The upper end of the steering post has secured to it a split collar 7 provided with upwardly extending ears 8 having bosses which receive a short shaft 9 upon which the metallic base 10 of a steering tongue 11 is pivotally mounted.

The base 10 of the steering tongue is provided with a rearward bifurcated extension 12 having a transverse pivot 13 upon which a strut 14 is so mounted that upon vertical swinging movement of the tongue the strut will be moved lengthwise substantially in the direction of the axis of the steering post. The upper end of the strut 14 is connected by a universal joint 15 to a swivel 16 which is rotatably mounted in the end of a pawl

actuating lever 17 operable, in the manner hereinafter to be described, to raise the load supporting means.

The load supporting means desirably is in 5 the form of a skeleton platform having side bars 18 connected at their front ends to a substantially vertical standard 19 having at its upper end a transverse shaft 20 upon which the lever 17 is mounted.

10 The load supporting means may be and desirably are supported upon mechanism similar to that illustrated in the Lovejoy patent above mentioned in which a lever, underlying the front end of the load supporting 15 means, is connected to a lifting link 21 which when raised substantially vertically raises the front end of the platform, with means operable by such supporting lever to raise the rear end of the platform.

20 The upper end of the lifting link 21 is pivotally connected to a sector-shaped lever 22 which is fulcrumed upon the shaft 20 and is provided at its free end with a series of ratchet teeth 23 adapted to be engaged by a 25 pawl 24 which is rigidly connected to a shaft 25 mounted in the lever 17 and provided with a handle 26. The pawl mechanism is so constructed that when the handle 26 is in the position illustrated the pawl 24 is held in 30 engagement with the ratchet 23 and a vertical downward swinging movement of the tongue will consequently raise the lever 17, thereby rotating the sector about the shaft 20 and acting through the link 21 will raise 35 the load supporting means one step.

Means are provided for locking the load supporting means against descent at each elevation. Upward swinging movement of the tongue will permit the lever 17 to descend so that the pawl will ride down over the ratchet to engage the next lowest tooth upon the same. Another downward movement of the swinging tongue will again raise the lever 17 as aforesaid to elevate the platform another step, where it will again be held by the locking mechanism. By repeating the operation above described the load supporting means may be raised to its maximum elevation.

40 The locking mechanism for retaining the load supporting means at each step of elevation comprises a ratchet 27 which is fixedly secured to the lifting link 21 and a co-operating dog 28 which is pivotally mounted upon 45 a shaft extending across the upper end portions of a pair of arms 29 which are pivoted at their lower ends upon a transverse girder of the main frame, which is not shown but which is fully disclosed in the patent to Lovejoy above mentioned. The locking dog 28 is normally held in engagement with the ratchet by a toggle or cam a member of which is rigidly fixed to a shaft 30 having an arm 31 provided with an outwardly extending stud 32 55 which extends into a slot in the upper end of

a link 33 the lower end of which is pivotally connected to an arm 34a of a pedal 34 which is mounted upon a stud shaft 35 carried by bosses or a bracket upon said cross girder of the frame. A spring 36, which is connected at its lower end to the arm 31 of the shaft 30, and at its upper end to a stud 37 projecting from a downwardly extending web on the lever 17, tends to rock the shaft 30 in a direction to retain the dog 28 in engagement with the teeth of the ratchet 27.

70 By reason of this construction the dog 28 will engage successively the notches of the ratchet 27 as the load supporting means is raised step by step and prevent the descent of the load supporting means, while the swinging tongue is moved downwardly to permit the pawl 24 to engage another tooth of the ratchet 23 upon the sector 22.

75 Rapid descent of the load supporting means is prevented by a vertical dash pot 38, the piston of which is connected at its upper end to a stud 39 projecting from a boss 40 upon the lifting link 21, while the lower end of the dash pot is pivotally supported upon 80 the transverse girder of the main frame.

85 The construction thus described is in all respects similar to that disclosed in the prior patent to Lovejoy above mentioned.

90 In the particular construction illustrated the means for preventing the release of the locking dog comprises a detent which normally engages the pedal 34 and prevents the depression thereof at all times except when the tongue is raised to a substantially vertical position from which it obviously cannot fly upwardly to injure the operator if the locking means is released, so that the load supporting means will descend.

95 As illustrated herein the detent 41 is of 105 arcuate form and is pivotally mounted upon a stud or bolt 42 which extends through the arched head of the main frame. The lower end portion of the detent is thickened to provide a counter weight 43 and is provided with a lateral extension 44 which normally underlies the pedal 34. The upper end of the detent desirably is provided with a flat abutment 45 of considerable area which lies in 110 proximity to the steering head.

115 In the construction illustrated the tongue extension 12 has secured to it, preferably by welding, a bracket 46 which is offset in such a manner that it will not engage the ear 8 of the steering post and a bunter 47 is pivotally mounted upon a stud 48 projecting from the bracket in such a manner as to depend therefrom by gravity, and when the tongue is in substantial alignment with the axis of the truck will overlie the abutment 45 of the detent 41. The length of the bunter 47 is such that when the tongue is swung upwardly and approaches substantially vertical position the lower end of the bunter 47 will engage the abutment 45 and when the 120 125 tongue is lowered the bunter 47 will be disengaged from the abutment 45.

tongue reaches vertical position will sufficiently depress the abutment to swing the lower end of the detent outwardly enough to remove the extension 44 from beneath the 5 pedal 34, thus freeing the pedal so that it may be depressed to release the load supporting means. Upon depression of the pedal, therefore, the link 33 acting upon the stud 32 will rotate the shaft 30 of the releasing 10 mechanism and permit or cause the dog 28 to be disengaged from the teeth of the ratchet 27, thereby permitting the load supporting means to descend.

Upon release of the pedal the spring 38 15 will raise the arm 31 of the rock shaft 30 and acting through the stud 32 will raise the pedal to normal position, thus permitting the detent to swing inwardly so that the extension 44 will again engage beneath the pedal and 20 prevent depression thereof.

By reason of the pivotal connection of the bunter 47 to the tongue extension, it will, upon lateral steering movement of the tongue, either pass over the abutment 45 when the 25 tongue is in substantially lowered position, or when the tongue is in elevated position will be caused to swing aside during the lateral movement of the tongue so that the bunter will in now way interfere with the steering 30 ing of the truck.

It will be obvious that by reason of this construction the load supporting means will be locked in all positions of elevation in such a manner that it cannot be released unless 35 the tongue is swung substantially to vertical position where it cannot possibly fly to injure the operator.

While a particular embodiment of the invention is disclosed herein as applied to an 40 elevating truck in which the load supporting means is raised step by step, it is obvious that the invention is equally applicable to elevating trucks in which a single vertical swinging movement of the tongue serves to 45 raise the load supporting means to its maximum height.

It is also obvious that the invention broadly disclosed herein may be embodied in different specific forms and may be applied not 50 only to trucks in which the load supporting means is raised by a vertical swinging tongue, but also to elevating trucks in which the load supporting means is raised by other forms of vertically swinging lifting levers 55 which will be likely to injure the operator upon release of the load supporting means, while the lifting lever is in such position that it will be caused to fly upwardly by the descent of the load supporting means.

Having thus described the invention, what is claimed as new, and desired to be secured by Letters Patent, is:

1. An elevating truck comprising load supporting means, means for lifting said 50 load supporting means including a lifting

lever mounted to swing vertically, releasable means for locking said load supporting means in raised position, and means normally engaging said locking means and acting to prevent release of said locking means 70 while said lifting lever is so co-ordinated with the lifting means that the descent of the load supporting means will cause the lifting lever to swing vertically.

2. An elevating truck comprising load supporting means, means for lifting said load supporting means including a lifting lever mounted to swing vertically, means for locking said load supporting means in raised position, means for releasing said locking means, a detent normally engaging said releasing means and preventing actuation thereof, and means operable only by the movement of said lifting lever to substantially vertical position 80 to disengage said detent.

3. An elevating truck comprising load supporting means, steering mechanism including a tongue mounted to swing vertically, means operable by a vertical swinging movement of the tongue to raise said load supporting means, releasable means for locking the load supporting means in raised position, and means normally engaging said locking means and acting to prevent release of said locking means while the tongue is so co-ordinated 90 with the lifting mechanism that the descent of the load supporting means will cause the tongue to swing upwardly.

4. An elevating truck comprising load supporting means, steering mechanism including a tongue mounted to swing vertically, means operable by a vertical swinging movement of the tongue to raise said load supporting means, means for locking the load supporting means in raised position, a 100 pedal operable upon depression to release said locking means, and means for preventing actuation of said pedal unless the tongue is in substantially vertical position.

5. An elevating truck comprising load supporting means, steering mechanism including a tongue mounted to swing vertically, means operable by vertical swinging movements of the tongue to raise said load supporting means step by step, means for locking said load supporting means at each step of elevation, means for releasing said locking means, a detent normally acting to prevent release of said locking means at any step of elevation, and means operable by said tongue only when swung to substantially vertical position to disengage said detent.

6. An elevating truck comprising load supporting means, steering mechanism including a tongue mounted to swing vertically, means operable by vertical swinging movements of the tongue to raise said load supporting means step by step, means for locking said load supporting means at each step of 120

elevation, means for releasing said locking means, comprising a pedal, a counterweighted detent having means normally extending beneath said pedal to prevent depression thereof, and a member vertically movable by the upward swinging movement of the tongue operable when the tongue is moved substantially to vertical position to engage said detent and remove the same from engagement with said pedal.

7. An elevating truck comprising load supporting means, steering mechanism including a tongue mounted to swing vertically, means operable by vertical swinging movements of the tongue to raise said load supporting means step by step, means for locking said load supporting means at each step of elevation, means for releasing said locking means comprising a pedal, a counterweighted detent having means normally extending beneath said pedal to prevent depression thereof, and a bunter pivotally mounted upon said tongue and depending therefrom operable when the tongue is moved substantially to vertical position to engage said detent and remove the same from engagement with said pedal.

8. An elevating truck comprising a frame having an arched head, steering mechanism mounted in said head having a tongue mounted to swing vertically to provide a rearward extension load supporting means, means operable by vertical swinging movements of said tongue extension to raise said load supporting means, means for locking said load supporting means at each step of elevation, means for releasing said locking means comprising a pedal, an arcuate counterweighted detent pivotally mounted upon said head to swing transversely of said frame and provided at its lower end with means normally extending beneath said pedal and at its upper end with an abutment lying in proximity to the steering head of said steering mechanism, and a bunter pivotally mounted upon said tongue extension and depending therefrom operable when the tongue is moved to substantially vertical position to engage said abutment and swing the extension on the lower end thereof from beneath said pedal.

In testimony whereof, I have signed my name to this specification.

DANIEL E. HENNESSY.
